UNITED STATES PATENT OFFICE.

JOHN J. BECKER, OF NEW YORK, N. Y.

MECHANICAL TOY.

Application filed February 21, 1927. Serial No. 170,015.

This invention relates to mechanical toys. One object of the invention is to provide a wheeled toy wherein characters in circus performances are characteristically displayed in appearance and action, particularly for the amusement of children.

Another object is to provide a wheeled toy of the nature stated, embodying among other characteristics, circus or other performers mounted for characteristic demonstration or action and which are set into motion from the running gear of the toy as it is rolled over a surface.

A still further object resides in the provision of a wheeled toy embodying a carriage and a support rising therefrom with figures or objects supported above the carriage to be revolved in at least one instance, and in other instances simultaneously revolved and rotated or tumbled.

With the above and other objects in view, the invention consists in the construction and novel arrangement of parts hereinafter described and set forth in the appended claims, it being understood that various changes in the form, proportion, and minor details of construction, within the scope of the claims, may be resorted to without departing from the spirit of the invention or sacrificing any of its advantages.

In the drawings:

Figure 1 is a view, partly in section and partly in elevation.

Fig. 2 is a top plan view with the circus master and clowns removed.

Fig. 3 is a fragmentary front elevation of one of the clowns.

Fig. 4 is a cross sectional view through the standard or post showing the fastening means for securing the fixed gear at the top of the standard or post.

Fig. 5 is a detail view of an object which may be substituted for the clowns.

Referring now more particularly to the accompanying drawings, the reference character A indicates a carriage, embodying a flanged body 6 of sheet metal or any other suitable material, provided adjacent its ends with pairs of wheels 7 and 8 mounted on suitable axles 9 and 10, respectively, the shaft 9 carrying a beveled gear 11 for a purpose presently explained. A wood or other post 12 rises from the body of the carriage, preferably centrally thereof, and it may be secured to the body of the carriage in any

suitable manner. As shown, the post has a marginal flange 13 at its lower end, through which, and the body, suitable fastening devices 14 may be employed to effect a substantial mounting connection between the post and the body of the carriage.

The post 12 is provided with a longitudinal bore 15, and a beveled gear 16 is fixedly mounted upon the upper end of the post and provided with a central opening 17 which aligns with the bore 15 of the post. The fixed connection between the beveled gear 16 and the top of the post may be effected by suitable fastenings 18 or otherwise.

A circus master is indicated at B. The body 19 of the circus master is preferably formed of wood, and this wood body, including the head, is provided with a high hat and frock coat, and has fixed arms 20 and 21 secured to the body 19, the hand 22 of the arm 20 carrying a whip 23.

A shaft 24 preferably square in cross section and pointed at its upper end, is driven well into the body 19 of the circus master from the under side thereof and extends downwardly through the opening 17 in the fixed beveled gear 16 and through the bore 15 of the post 12 to a point under the body 6 of the carriage A and is supported in such position by said circus master body 19.

A metal hanger C is secured intermediate its ends, as at 25, to the underside of the circus master body 19, by means of suitable fastenings 26. This hanger C has vertical depending portions 27 and outwardly directed horizontal portions 28 which terminate at their outer ends in upturned portions 29 aligning with the depending portions 27.

Shafts 30 and 31 are journaled in bearings 32 in the cooperating portions 27 and 28 of the hanger C. These shafts are square in cross section and the bearings 32 are circular but large enough in cross section to permit rotation of the shafts 30 and 31. Beveled gears 33 and 34 are keyed one to the inner end of each of the shafts 30 and 31, respectively, and these gears are held within the depending portions 27 of the hanger C in mesh with the adjacent fixed gear 16 on the top of the post 12. If this fixed gear 16 is of a form other than a beveled gear, the gears on the shafts would be of corresponding type for cooperation therewith. In any event, the outer ends of the shafts 30 and 31 are pointed as shown, so as to be readily

driven into a wood body 35 of a figure representing a clown or other character. These shafts 30 and 31 being square in cross section, the connection between them and the bodies 35 of the clowns or other figures is such as to prevent accidental turning of the figures on the shafts. Arms 36 are secured to each body 35 of the clowns or other figures for swinging movement, and this may be accomplished by mounting said arms 36 on a cord 37 passing longitudinally through the arms 36 and transversely through the body 35 of each clown or other figure. A bell 38 may be secured to the body of each clown or other figure to ring as the arms of the clown or other figure swing as the body tumbles under the influence of rotation of the shafts 30 and 31. The operation of the toy is such that the shafts 30 and 31 revolve horizontally and carry the clowns or other figures 35 around with them. The clowns or other figures, during this revolving movement, are caused to rotate or tumble in substantially vertical planes.

To operate the shafts 30 and 31 to give the actions stated immediately above, the shaft 24 is driven to revolve the circus master B and consequently give similar movement to the hanger C, carried by the circus master body. As the hanger C is thus revolved, and as it carries the shafts 30 and 31 and the respective gears 33 and 34, and the latter being in mesh with the fixed gear 16, the shafts 30 and 31 are rotated in opposite directions and rotate or tumble the clowns or other bodies, and accordingly, jingling the bells 38, carried by the clowns.

The shaft 40 is driven from the front carriage axle 9 on which the aforesaid beveled gear 11 is fixed. This gear 11 meshes with a beveled gear 39 on the outer end of a drive shaft 40 journaled in a suitable hanger 41 riveted or otherwise secured to the underside of the body 6 of the carriage. A beveled gear 42 on the inner end of the drive shaft 40 meshes with a beveled gear 43 on the lower end of the driven shaft 24, the latter extending through an opening in the body of the carriage A.

Thus as the toy or device is rolled on its wheels over a surface, the rotatable front axle imparts rotative movement to the drive shaft 40 through the gear mechanism 11—39, and the drive shaft imparts rotative movement to the driven shaft 24 through the medium of the gear mechanism 42—43 to revolve the circus master body 19. As the latter revolves it causes the hanger C, fixed thereto, to revolve with it. As the clown body carrying shafts are journaled in the hanger C, they also revolve with the hanger carrying the clowns or other figures 35 around in a circle, and while thus being carried around in a circle, the clowns are given a continuous tumbling action, due to ro-

tation of the shafts 30 and 31 incident to their gears 33 and 34, respectively, operating over the fixed gear 16 at the top of the post 12. The hanger C, being fixed to the body B supports all of the device above the carriage, and also supports the driven shaft 24.

To pull the carriage A over a surface, a suitable handle may be provided, or it may be pulled by a rope or cord 45 knotted and passed through an opening 46 in the front flange of the carriage, as shown in Fig. 1.

The gear mechanism 11—39 and 42—43 may be of forms different from that illustrated, and figures or objects other than clowns 35 may be carried by the outer ends of the shafts 30 and 31. For instance, a device D such as shown in Fig. 5 may be substituted for the clowns. This device D has a hub 47 to be fitted on the outer ends of the shafts 30 and 31 and provided with radial arms 48 carrying spherical shaped members 49 at their outer ends.

The figures may be variously colored to suit the nature or characteristics of the clowns, circus master, or other characters, and where figures or objects other than representative of humans are employed the same may be colored as desired for attractiveness.

What is claimed is:

1. In a device of the character described, a wheeled carriage and supporting means rising from the carriage, a vertical shaft extending upwardly through the carriage and through and beyond said supporting means, a member pierced by the upper end of said shaft whereby to secure said member fixedly to the shaft above the supporting means, a hanger fixedly secured to the bottom of said member and supported thereby and which depends therefrom in spaced relation to said supporting means and including an inverted U-shaped body portion and oppositely directed arms projecting from said body portion, each arm terminating in an upwardly directed portion provided with bearings, straight shafts rotatably mounted one at each end in said U-shaped inverted body portion of the hanger and at its other end rotatably mounted in the bearing portion of the respective arms, the last mentioned shafts being arranged in substantially horizontal alignment and having their inner ends spaced from each other, a member fixedly mounted on the outer end of each horizontal shaft, means operatively connected to said vertical shaft, whereby upon rolling motion of the carriage the vertical shaft is rotated and the first mentioned member carried by the vertical shaft is also rotated and said hanger revolved, and means whereby upon said rolling motion of the carriage said horizontal shafts are rotated in opposite directions as they are carried around by the

revolving hanger to rotate the members with the horizontal shafts in opposite directions and in vertical planes.

2. In a device of the character described, 5 a wheeled carriage and supporting means rising from the carriage, a vertical shaft extending through the carriage and through said supporting means, a member secured fixedly to the shaft at the upper end thereof 10 of above the supporting means, a hanger fixedly secured to the bottom of said member for support thereby and depending therefrom in spaced relation to said supporting means and including oppositely extending arms, oppositely disposed straight shafts journaled in the hanger and arranged 15 horizontally in parallelism with the arms of

the hanger, a member fixedly secured on the outer end of each horizontal shaft, means whereby upon rolling motion of the carriage 20 the vertical shaft is rotated to revolve the member carried thereby and also to revolve said hanger, and means operatively connected with the horizontal shafts, whereby upon said rolling motion of the carriage the horizontal shafts are rotated in opposite directions as they are carried around by the hanger so as to rotate the members in vertical planes and in opposite directions during 25 revolution of the hanger in the manner aforesaid.

In testimony whereof I have hereunto set my hand.

JOHN J. BECKER.
